US0D1113955S

(12) **United States Design Patent** (10) Patent No.: **US D1,113,955 S**
Peters et al. (45) Date of Patent: ** Feb. 17, 2026

(54) **DISPLAY SCREEN WITH GRAPHICAL USER INTERFACE**

(71) Applicant: **ContiTech Deutschland GmbH**,
 Hannover (DE)

(72) Inventors: **Chad Peters**, Bastian, VA (US); **Dillon Carter**, Valparaiso, IN (US); **Nathaniel Weber**, Rockford, IL (US); **Cameron Banga**, Valparaiso, IN (US)

(73) Assignee: **ContiTech Deutschland GmbH**,
 Hannover (DE)

(**) Term: **15 Years**

(21) Appl. No.: **29/951,148**

(22) Filed: **Jul. 8, 2024**

(51) LOC (15) Cl. **14-04**

(52) U.S. Cl.

USPC **D14/486**; D14/492

(57) **CLAIM**

The ornamental design for a display screen with graphical user interface, as shown and described.

DESCRIPTION

The FIGURE is a front view of a display screen with graphical user interface showing the new design.

The outermost broken line rectangle shows the display screen, and forms no part of the claimed design. All other broken lines show portions of the graphical user interface and form no part of the claimed design.
